Primary Examiner — George D. Kirschbaum*(74) Attorney, Agent, or Firm* — Reilly Intellectual Property Law Firm(57) **CLAIM**

The ornamental design for parking block, as shown and described.

DESCRIPTION

FIG. 1 is a top perspective view of a parking block, showing the design;

FIG. 2 is a top view of FIG. 1;

FIG. 3 is an end view of FIG. 1;

FIG. 4 is a side view of FIG. 1;

FIG. 5 is an opposite side view of FIG. 4;

FIG. 6 is an opposite end view of FIG. 3;

FIG. 7 is a bottom view of FIG. 1;

FIG. 8 is a top perspective view of a related form of parking block;

FIG. 9 is a top view of FIG. 8;

FIG. 10 is an end view of FIG. 8;

FIG. 11 is a side view of FIG. 8;

FIG. 12 is an opposite side view of FIG. 11;

FIG. 13 is an opposite end view of FIG. 10; and,

FIG. 14 is a bottom view of FIG. 9.

The broken line showing is included for the purpose of illustrating portions of the “article” and forms no part of the claimed design.
